Primary Examiner — T Chase Nelson*Assistant Examiner* — Rachel Wolfe(57) **CLAIM**

The ornamental design for a table lamp, as shown and described.

DESCRIPTION

FIG. 1 is a first perspective view of a table lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the table lamp thereof; and,

FIG. 10 is an enlarged view of the selected portion in FIG. 2.

The broken lines shown in the drawings depict portions of the table lamp in which the design is embodied that form no part of the claimed design. The broken lines of alternating length in FIGS. 2 and 10 are for the purpose of illustrating the boundaries of the enlarged fragment shown in FIG. 10 and form no part of the claimed design.
